ABSTRACT

An axial blast interruption chamber for self-blasting compressed gas electric circuit-breakers, having a blast orifice unit internally shaped to provide, in the outlet direction, a conical convergent zone; a cylindrical zone having the smallest surface in comparison with the other internal zones, in which a plurality of decompression holes is located, the mouth sections of these holes being parallel to the axis of the interruption chamber; and a substantially conical divergent zone, the divergent zone having a plurality of ring-like grooves, each of which is of substantially triangular cross section with an open base disposed towards the outlet orifice of the interruption chamber; wherein the decompression holes have substantially the shape of oblique truncated cones with their axis slanting in the gas outflow direction; an external shell concentrically surrounding the interruption chamber; and a toroidal groove concentrically disposed in the shell, having a substantially triangular cross section with an open base disposed in the direction of the outlet orifice, the generatrix of the toroidal groove slanting in the gas outflow direction, the outlet sections of the decompression holes opening into the toroidal groove.

FIG. 1

FIG. 2

**BLAST ORIFICE UNIT FOR SELF-BLASTING
COMPRESSED GAS ELECTRIC CIRCUIT-BREAKERS**

BACKGROUND OF THE INVENTION

1. Field of the Invention

The object of this invention is an improved blast orifice unit for self-blasting compressed gas circuit-breakers, which greatly increases the performance of the interruption chambers with which these circuit-breakers are equipped in comparison with the known prior art types.

2. Description of the Prior Art

Compressed gas circuit-breakers are already well known and widely used in electric plant construction; particularly well known are the axial blast interruption chambers, used in this type of circuit-breaker, the shape of which has, in its various styles, been determined through well established principles.

Italian Pat. No. 791,651 concerns an axial blast interruption chamber for self-blasting compressed gas electric circuit-breakers provided with an orifice unit having decompression holes and ring-like grooves shaped to promote the escaping of both the gases developed by the decomposition of the materials making up the interruption chamber and the quenching gas, thereby obtaining a concomitant flow of the first and latter mentioned gases. The shape of the lower part of the interruption chamber is determined with respect to the circuit-breaker rated service voltage according to the experimental relation:

$$L \geq \frac{U_n}{\sqrt{3}} \cdot (1.5) \cdot \sqrt{2};$$

or, after simplification:

$$L \geq \sqrt{1.5 \cdot U_n},$$

where L stands for the chamber end part length stated in mm, and U_n is the circuit-breaker rated service voltage expressed in kV.

It has been found, however, that the axial blast interruption chambers so far known do not attain top performance with respect to the arc quenching gas exhaust and the protection of the parts external to the chamber against the action of the arc. This performance lack applies as well to the displacement speed of the moving parts within the chamber on which the disengagement of the moving from the fixed contact of a single-pole circuit-breaker directly depends.

SUMMARY OF THE INVENTION

An object of this invention is therefore to obtain the best possible performance of an interruption chamber for compressed gas circuit-breakers, structurally improved with respect to present devices and with particular reference to the interruption chamber of the aforementioned Italian patent.

A further object of this invention is to improve the decompression in the zone around the mouths of escape holes in the walls of the interruption chamber, thereby facilitating the escape of the quenching gas from the chamber.

A still further object of this invention is to improve and accelerate the outflow of decomposition and quenching gases through the exhaust orifice of the chamber and decreasing the whirling effects occurring in said outlet flow.

A still further object is, moreover, to efficiently protect the parts external to the chamber, and particularly the insulating cylinder, in bakelized paper, or other similar insulation housing externally wrapping the chamber, against the effects of the interruption electric arc.

Finally, still another object is an interruption chamber through which at least a part of the quenching gas, suitably directed, cooperates with the circuit-breaker control devices to speed up the circuit-breaker switching off operation.

These and other objects, which will be more fully described hereinafter, are obtained by an axial blast interruption chamber for self-blasting compressed gas electric circuit-breakers, said interruption chamber having a blast orifice unit internally shaped to provide, in the outlet direction, a first

conical and convergent zone and a second cylindrical zone, the latter having the smallest surface in comparison with the other internal zones. A plurality of decompression holes is located in the second cylindrical zone, wherein the mouth sections of these holes are disposed parallel to the axis of the interruption chamber.

The chamber further comprises a third substantially conical and divergent zone, the length of which is determined from the aforementioned experimental relation:

$$L \geq \frac{U_n}{\sqrt{3}} \cdot (1.5) \cdot \sqrt{2}.$$

This third divergent zone includes a plurality of ring-like grooves, each of which has a substantially triangular cross section with open base disposed in the direction of the outlet orifice of the interruption chamber. In the interruption chamber, the decompression holes have substantially the shape of oblique truncated cones, their axes defining, together with the axis of the interruption chamber, angles less than 90° in the outflow direction; these holes are made through the common wall of the interruption chamber corresponding to the second, cylindrical, and smaller surfaced zone where they have their mouth.

25 A concentric external shell surrounds the interruption chamber proper and has an outer diameter greater than the outer diameter of the chamber. A toroidal groove or slot is defined in the shell concentrically to the interruption chamber, this groove having a substantially triangular cross section with an open base disposed in the direction of the outlet orifice of the interruption chamber. The generatrix of the toroidal groove, which is farther off from the bore axis that coincides with the interruption chamber axis defines, together with the chamber axis, an angle of less than 90° in the gas outflow direction. The outlet sections of the decompression holes open on this groove, the shell and groove comprising a protective shield which completely covers the outlet sections, the shell preferably being made of the same material as the interruption chamber and formed in one piece therewith or, alternatively, consisting of one or more parts distinct from but coupled in close contact with the interruption chamber.

BRIEF DESCRIPTION OF THE DRAWING

45 The interruption chamber which is the subject of this invention will be hereinafter described in detail with reference to the attached drawing, wherein:

FIG. 1 schematically shows the longitudinal section of an interruption chamber part comprising both the small surfaced zone, with its outward communicating holes (or decompression holes), and the conical divergent end zone; and

50 FIG. 2 shows, on a larger scale, the detail of a decompression hole in the smaller surfaced zone.

DESCRIPTION OF THE PREFERRED EMBODIMENT

Referring to FIGS. 1 and 2, the improved blast orifice unit of the interruption chamber of this invention comprises a shell 4, made of the same material as the interruption chamber and constructed as a single piece therewith, surrounding the interruption chamber and axially extending to enclose, in the gas outflow direction, the first conical convergent zone 1, the second cylindrical and smaller surfaced zone 5 and finally, at least partially, but sufficiently to fully shield outlet sections 11 60 of decompression holes 6, the third conical divergent zone 9; shell 4 consequently has a larger outer diameter than the outer diameter of the interruption chamber proper.

Decompression holes 6 are formed in the wall of the interruption chamber corresponding to cylindrical zone 5, and are inclined towards zone 9. The mouth sections 10 of holes 6, which open into the interruption chamber, are parallel to axis A—A of the chamber itself, due to the shaping of said zone 5, and consequently are parallel to the gas flow direction shown by arrows 7 (the direction of gas flow being parallel to axis A—A).

Holes 6, unlike prior art constructions, do not have their axes perpendicular to axis A—A of the interruption chamber; their shape therefore is not the standard right truncated cone shape of the holes adopted by the known technique; on the contrary, as previously noted, they have an oblique flow axis from zone 5 towards zone 9, the flow axis being therefore inclined in the gas outflow direction, towards axis A—A, by an angle α that, according to the preferred embodiment of this invention, ranges from 45° to 65°. The holes which pass through the wall of the interruption chamber proper have their outlet sections referenced 11.

Further, unlike the known prior art, however, these holes do not open through section 11, directly into open air; rather they open into annular groove or slot 16 in the shell 4. Groove 16 is disposed concentrically to the interruption chamber, and has a substantially triangular cross section with an open base 12 directed in the same direction as outlet orifice 2 of the interruption chamber; and, on the drawing plane, base 12 also denotes the mark of the ring which is the open air outflow section of groove 16. Groove 16 can be deemed a toroidal body generated by the substantially triangular geometrical figure defined by sides 11, 12 and 19 in FIGS. 1 and 2, said figure being supposed as revolving around axis A—A of the chamber, which consequently becomes coincident with the tore axis. According to this invention, the generatrix line of the toroidal body, coincident with the side 19 and opposed, on the drawing plane, to the mark of the outlet section 11, is inclined, in the outflow direction and towards axis A—A, at an angle β ranging from 30° to 45°.

As shown by the arrows in FIG. 2, the arrangement of the decompression holes 6 and their particular shaping determine the flow of quenching gas therethrough. Each slanting truncated cone hole 6 directs the flow of quenching gas along arrows 8; then the gas reaches groove 16 and at side 19 strikes against the protective shield formed thereby, thus undergoing a deflection in the direction of arrows 17 substantially parallel to axis A—A and to inner flow 7.

Several advantageous results are achieved with this arrangement. First, a regularization in the streaming of the gas flow through the decompression holes 6 is obtained, whereby the exhaust from these holes is facilitated with a consequent quicker decompression of cylindrical zone 5; the whirl phenomena inside zone 5, in particular, and inside the whole interruption chamber generally, is decreased to a negligible amount.

Secondly, the final flow of the gas becomes substantially parallel to axis A—A of the chamber and can thus join the gases exiting from outlet opening or orifice 2 of the chamber without giving rise to any whirl phenomena.

Thirdly, shell 4, and in particular, the protection shield established in zone 19 by this shell, prevents the hot gas (heated in consequence of its contact with the arc) exiting from holes 6 from coming in contact with the cylinder 20 made of bakelized paper or other suitable insulating material. The efficient protection of cylinder 20 is in this way obtained, thereby prolonging its operational life.

Finally, a further advantage ensuing from this invention (an advantage wholly non-existent in the devices of the known prior art) consists in obtaining a thrust which improves the opening of the circuit breaker by accelerating the displacement of the moving part (in the direction of arrow 18) with which moving contact 3 is jointed. In fact, the gas flowing in the direction of arrows 8, strikes side 19 and develops a thrust against shell 4. The effects of this thrust can be analyzed by resolving it in two orthogonal directions, one parallel to axis A—A and the other perpendicular thereto; the component according to the latter direction has no effect on the movement of the chamber, since the interruption chamber has no displacement perpendicular to axis A—A, whereas the component parallel to axis A—A improves the circuit breaker opening (see arrow 18, FIG. 2).

The advantages obtained by this invention are increased by the advantages due to the particular shape of the lower part 9

of the chamber which is provided with triangular cross-sectioned ring-like grooves 13. In fact, resultants 15 of generation lines 14 of the decomposition gases present a component parallel to axis A—A which improves both the outflow of the quenching (or deionizing) gas and the decomposition gas.

The invention as hereinabove described, exemplified, illustrated and hereunder claimed, can be modified without going outside the scope thereof. For example, shell 4 can be extended in the outflow direction so that it surrounds (besides zones 1 and 5) not only a part but the whole of zone 9, thus making decompression holes 6 open into groove 16, extending in a hollow having a right cross section in the form of a ring which coaxially surrounds the whole interruption chamber and has its outlet end section (equivalent to section 12) laying in the same plane as the outlet opening or orifice 2 of the chamber. Alternatively, decompression holes 6, instead of opening into annular groove 16, can continue on in single outflow ducts which are direct extensions of holes 6 and have cross sections corresponding to the shape of holes 6 or join in a suitable manner with their outlet sections 11. It is possible that outflow ducts 16 would in turn terminate with their own section 12, as shown, or continue on unchanged beyond section 12 to terminate in the same plane as outlet orifice 2, in case the shell 4 is extended to include the whole of zone 9. It may be also noted that the cross section of outflow ducts 16 can be circular, elliptical, or have any other suitable and convenient shape; this also applies to the cross section of decompression holes 6, although in regard to this point, it has been confirmed that the circular cross section is preferable in comparison with others. Also, the device contains at least two decompression holes 6; the preferred embodiment employs four, displaced from each other by 90°, although it is considered possible to foresee more than four.

What is claimed is:

1. An axial blast interruption chamber for self-blasting compressed gas electric circuit breakers, comprising a blast orifice unit having a conical convergent zone, a cylindrical zone, a plurality of decompression holes operatively associated with said cylindrical zone, the plane of the mouth sections of said holes being disposed parallel to the axis of said interruption chamber, and a substantially conical divergent zone, the length of which is determined by the relation:

$$L \geq \frac{U_n}{\sqrt{3}} \cdot (1.5) \cdot \sqrt{2};$$

said divergent zone containing a plurality of ring-like grooves having substantially triangular cross sections with an open base disposed in the direction of the outlet orifice of said interruption chamber; wherein said decompression holes have a substantially oblique truncated cone shape with their axes slanting in the direction of gas outflow at an angle (α) less than 90° towards the axis of said interruption chamber; an external shell concentrically surrounding at least a portion of said interruption chamber; a toroidal groove concentrically disposed in said shell, having a substantially triangular cross section with an open base disposed in the direction of said outlet orifice, the generatrix of said toroidal groove slanting in the direction of gas outflow at an angle (β) less than 90° towards said chamber axis; outlet sections of said decompression holes opening into said toroidal groove; said shell and said toroidal groove comprising a protective shield which completely covers said outlet sections.

2. An interruption chamber according to claim 1, wherein said angle (α) ranges from 45° to 65°.

3. An interruption chamber according to claim 1, wherein said angle (β) ranges from 30° to 45°.

4. An interruption chamber according to claim 1, wherein said shell axially extends in said gas outflow direction and surrounds at least said convergent zone, said cylindrical zone, and at least a part of said divergent zone, wherein said shell substantially fully shields said outlet sections.

5. An interruption chamber according to claim 1, further comprising at least four decompression holes, adjacent holes

having their axes disposed substantially at right angles to one another.

6. An interruption chamber according to claim 1, wherein said shell comprises a single unit with said interruption chamber.

7. Interruption chamber according to claim 1, wherein said shell comprises at least one part distinct from and in close contact with said interruption chamber.
